VACUUM-BOTTLE SUPPORT.

1,143,173.

Specification of Letters Patent. Patented June 15, 1915.

Application filed January 14, 1915. Serial No. 2,156.

To all whom it may concern:

Be it known that I, FREDERICK E. CARLSON, a citizen of the United States, and a resident of New Britain, county of Hartford, State of Connecticut, have invented new and useful Improvements in Vacuum-Bottle Supports, of which the following is a specification.

In the manufacture of double-walled 10 vacuum receptacles, it is customary to insert a support or supports between the walls so as to steady one from the other to prevent relative vibration which would tend to, cause the glass to crack at the neck where 15 the two bottles are sealed together to inclose the vacuum space.

This invention relates to a new form of support and its combination with the double-walled vacuum receptacle.

20 In the drawings—Figure 1 is a sectional side view, showing the vacuum receptacle equipped with supports made in accordance with my invention. Fig. 2 is a transverse sectional view on enlarged scale. Fig. 3 is 25 a detail view of the support.

Referring to the drawings, *a* denotes the outer bottle and *b* the inner one, the two bottles being sealed together at the neck *c*, and after the supports have been introduced 30 between these walls the bottom of the outer bottle is closed in as indicated in dotted lines in Fig. 1.

A support made in accordance with my invention comprises a bar 5 of resilient or 35 spring metal curved from end to end. This bar is located between the walls of the vessel, its curvature being in the same direction as the curvature of the walls of the vessel but being on a larger radius, so that while 40 its central portion lies against the inner wall, its ends stand free of the inner wall and adjacent to the outer wall. In fact, in the preferred embodiment of the invention the ends of this bar are bent outwardly and 45 back upon the bar to form clips, as clearly shown in the drawings. Furthermore, to eliminate any path for heat conduction between the inner and outer walls, a heat non-conducting material is interposed between 50 one of the walls and the most adjacent part of the support. For instance, as shown, the heat insulating material is wound about the folded over ends of the bar and is in the form of a strip of insulating material 55 such as asbestos paper, one end of a strip

being caught in the clips which are formed by folding over the ends of the bar, and so wound as to lie between the bar and the outer wall. These supports, it will be noted, are comparatively short, considerably less than the semi-circumference of the bottles, and are manufactured with such a curvature that they must be sprung slightly in order to insert them between the walls. In this way, and because the bars are curved in the same general direction as the walls of the bottle, the supports exert a light spring action tending to spread the walls apart, and a plurality of the supports are used with the result that while the walls are not held rigidly they are nevertheless very efficiently supported, and any slight motion they may have, due to a jar or shock, is always backed up and followed up by the spring action of the support. It is a material feature of 75 this invention that the curvature of the support shall be in the same direction as the curvature of the walls, since by this arrangement the lightest and most delicate spring action is to be had. If the receptacle contains heated material these metallic supports are apt to expand, and the fact that they curve in the same direction as the walls of the bottle leaves their ends free to move slightly under expansion without 85 subjecting the walls to undue pressure which would be the result if the curvature were in a direction opposite to the curvature of the walls.

It is advisable to have the heat non-conducting material at the ends of the support where it bears against the outer wall, since these are the points which have such relative motion as there is, and the material not only acts as a heat non-conductor, but also 95 as a cushioning pad.

I am aware of the structures disclosed in the British patent to Chassel 1561/1911, and do not wish to be understood as claiming as my invention any of the structures there 100 illustrated.

A feature of this invention to which it is desired to direct particular attention, is the relative curvature of the support and the bottle walls, and the points of contact between the support and the bottle walls.

I claim as my invention—

1. The combination with a double-walled vacuum insulated vessel of fragile material, of means for spacing and supporting the 110

walls from one another, said means comprising a resilient strip of metal arranged circumferentially between the walls, said strip curved from end to end in the general direction of the curvature of the walls but on a larger radius, bearing at its central portion against the inner wall and at its end portions against the outer wall, and heat insulating material interposed between one wall and the part of the support bearing thereagainst.

2. The combination with a double-walled vacuum insulated vessel of fragile material, of means for spacing and supporting the walls from one another, said means comprising a resilient strip of metal arranged circumferentially between the walls of the vessel, the curvature of said strip being on a larger radius but in the same general direction as the curvature of said walls, the ends of said strip being bent backwardly upon itself opposite to the direction of curvature, the central portion of said strip bearing against the inner wall, the ends of said strip bearing against the outer wall, and heat insulating material wound about the bent-back end portions of the strip and interposed between it and the outer wall.

3. The combination with a double-walled vacuum insulated vessel of fragile material, of means for spacing and supporting the walls from one another, said means comprising a resilient strip of metal arranged circumferentially between the walls and con-

tacting at its central part with the inner wall, the portions of said strip at either side of its central contacting point bent inwardly slightly, the ends of said strip terminating adjacent the outer wall, and heat non-conducting material attached to the ends of said strips and contacting with the outer wall at spaced points.

4. The combination with a double-walled vacuum insulated vessel of fragile material, of means for spacing and supporting said walls from one another, said means comprising heat non-conducting material engaging the outer wall at spaced points, and a resilient inwardly bent strip having its ends connected to said non-conducting material and its central portion bearing upon the inner wall only.

5. The combination with a double-walled vacuum insulated bottle made of fragile material, of means for spacing and supporting said walls from one another, said means comprising a strip of resilient material arranged transversely in the space between said walls and contacting at its central portion with said inner wall, and at its ends with said outer wall, the end portions of said strip at either side of its center being arranged at not more than a right angle with respect to the radial line at its center.

FREDERICK E. CARLSON.
